GEORGE BURNSIDE FLOOD, OF NORTH ADAMS, MASSACHUSETTS.

KEIR-BLEACHING.

1,290,156.

Specification of Letters Patent.

Patented Jan. 7, 1919.

Application filed May 17, 1918. Serial No. 235,169.

To all whom it may concern:

Be it known that I, GEORGE BURNSIDE FLOOD, a citizen of the United States, and a resident of North Adams, in the county of

5 Berkshire and State of Massachusetts, have invented new and useful Improvements in Keir-Bleaching, of which the following is a specification.

This invention particularly relates to a 10 method of securing a constantly uniform action of the bleaching liquor upon the textile materials to be bleached within an ordinary bleaching-keir and to an apparatus for insuring the practically continuous circulation of the bleaching liquor whereby 15 such method may be practised.

In keir-bleaching as usually performed the textile materials to be bleached are deposited within the keir in such manner as 20 to constitute a mass filling the body of the keir laterally and resting upon a grating located near the bottom of the keir. The bleaching liquor with which the keir is charged at the outset of the operation, per- 25 colates through the mass of textile materials and drains away into a receptacle below the grating whence it is by suitable means re- turned to the upper part of the keir above the mass of textile materials. In accom- 30 plishing this circulation the bleaching liqu- or is commonly introduced at the top of the keir through a distributing contrivance which delivers it there in a spray. Provi- 35 sion is also made for the introduction of steam into the upper part of the keir to heat the bleaching liquor and this inci- dentally creates more or less steam-pressure above the surface of the liquid.

Heretofore there have been mainly em- 40 ployed three different modes of circulating the bleaching liquor by returning it from beneath the grating at the bottom of the keir through which it drains to the top of the keir above the mass of textile materials 45 undergoing bleaching.

One of these modes has been practised by 50 means which characterize the well-known injector-keir, so-called, wherein a jet of steam is discharged into a pipe leading from beneath the drainage grating to the space within the top of the keir, and is projected in a direction to force the bleaching liquor to return again above the mass of textile materials to be bleached. Some- 55 times more than one such return-pipe and steam injector have been provided; but the

circulation thus effected is irregular and un- 60 certain by reason of the variations of tem- perature and pressure which occur within the keir.

By another of the prior modes referred to, the circulation has been effected by a double-acting pump which sucks the bleaching liquor from a closed well at the bottom of the keir below the drainage-grating and 65 forces it into the top of the keir again. But this operation although performed by mech- 70 anism which is regular and continuous in its working is attended with serious draw- backs because it is independent of the work 75 actually required to be done. It has not been found feasible to adjust the action of a suction pump in such manner as to main- 80 tain a withdrawal of bleaching liquor from the bottom of the keir at all times equal in amount to the rate of drainage through the grating. Each successive charge of textile materials introduced into the keir has its own peculiarities of lodgment therein and its own permeability to the bleaching liq- 85 uor; so that even when such textile mate- 90 rials are ostensibly of the same kind the rate of drainage through the grating will be variable from charge to charge and can- not be determined beforehand. Much more 95 is this the case when the charges of textile materials to be bleached differ from one an- other in kind. Hence, even if the circulat- 100 ing pump were capable of adjustment to vary its amount of intake and delivery, it could not be made to accommodate with any certainty the conditions presented in a given fresh instance.

If the capacity of the pump is insufficient 95 to take care of all the drainage freely flow- ing from the grating when unobstructed below, the consequent flooding of the grating by the accumulation of liquid beneath it will check the percolation of the bleaching liquor through the textile materials and thus 100 retard the action of the scouring process; and if, on the other hand, the capacity of the pump is such as to gain upon the rate of drainage the suction will finally come to be exerted directly upon the air-space be- 105 low the grating and will by the partial vacu- um created thereby solicit the percolation of the bleaching liquor through the mass of textile materials in such manner as to cause unequal flow therein along paths of 110 relatively differing resistance which will re- sult in uneven bleaching showing itself in

streaks upon the goods when withdrawn from the keir.

The operation of this pumping system of circulation is likewise attended with mechanical difficulties due to the corrosive action of the bleaching liquor in contact with the working parts of the pump and resulting in obstructions, leakage and other disturbances which require frequent and expensive remedying.

To avoid these drawbacks, still another mode of circulating the bleaching liquor has been adopted whereby the liquid draining through the grating is allowed to run off by simple gravitation through a duct provided with a check-valve opening outward into a trap from which it is periodically raised and discharged into the top of the keir, by steam-pressure acting as a gaseous piston upon the upper surface of the liquid contents of the trap. During this action and by reason of it the check-valve of the duct leading from the bottom of the keir is closed and the conditions beneath the grating remain undisturbed, except by the accumulation of drained liquor there.

But this mode of circulation as heretofore practised is necessarily intermittent, with intervals of cessation in the return of the drained bleaching liquor into the keir again, in each instance equal at least to the time allowed for charging the trap; so that corresponding fluctuations of very considerable extent occur within the keir in the quantity of bleaching liquor remaining in contact with and percolating through the mass of textile materials to be bleached; and consequently the rate of percolation is retarded and the duration of the bleaching process is greatly prolonged.

The object of the present invention is to obviate the defects of the prior modes of circulation referred to while retaining such advantageous features as either of them may have possessed; and this object is effected by a method and means which secure a practically continuous circulation of the bleaching liquor and therefore the maintenance of its quantity in contact with and percolating through the mass of textile materials to be bleached within the keir, substantially constant.

The apparatus by means of which my new method of keir-bleaching may be practised is represented in the accompanying drawings wherein Figure 1 shows the several constituents thereof in elevation with the lower portion of the keir broken away to exhibit the position of the grate therein, while Fig. 2 and Fig. 3 show in detail the construction and arrangement of the mechanism for periodically opening and closing the steam-valves which control the pumping functions of the apparatus.

The keir A is of ordinary construction,

provided with a man-hole B, spraying device C, boiling steam-pipes D having controlling valves d, and draining grating E. From the bottom of the keir lead two separate ducts F and F', each of which terminates in a trap G or G' and contains a check-valve H or H' opening outward. Each trap G or G' constitutes a liquid holding receptacle entirely closed except in so far as concerns the duct leading thereto, already mentioned, and certain pipe connections presently to be specified.

A circulating return-pipe I or I' open at its lower end, extends upward from near the bottom of each trap and terminates in the spraying device C within the top of the keir. Each return-pipe contains at its upper part above the level of its entrance into the top of the keir a check-valve J or J' opening toward this entrance. A steam-pipe K or K' extends from the top of each trap to a source of steam-supply (not shown), and is provided with a valve L or L' which is made to open and close for the admission and exclusion of steam at regular intervals of time by mechanical connection to a uniformly rotating shaft in such manner that when the valve L of one steam-pipe K is opened the valve L' of the other steam-pipe K' is closed, and vice versa; so that while the bleaching liquor which had previously flowed into one trap is by steam-pressure being raised therefrom and discharged into the top of the keir, the bleaching liquor which meantime continues to drain through the grating is flowing into the other trap; and thus the circulation maintained by the entire apparatus is such that the bleaching liquor is returned to the top of the keir at a quantitative rate very closely approximate to the rate at which it drains through the grating whereby the quantity of bleaching liquor in contact with and percolating through the mass of textile materials to be bleached within the keir is maintained substantially constant.

A vent pipe M or M' leads from the top of each trap into the upper part of the circulating return-pipe I or I' just short of the check-valve J or J' to aid in restoring the equilibrium of conditions within the trap after its liquid contents have been discharged into the top of the keir and when such trap is due to receive again the inflow of bleaching liquor draining through the grating.

A pressure gage a upon a pipe communicating with the interior of the keir A is provided for indicating the degrees of steam-pressure therein; and pressure gages g and g' are similarly connected respectively with the traps G and G'.

The charge of bleaching liquor may be introduced into the keir from below through the supply pipe N and may be drawn off

through the waste pipes O, while the washing water is let in at the top through the pipe P and is delivered upon the mass of textile material through the spraying device 5 C. Blow-off pipes Q are also provided for clearing the apparatus.

The valves L and L' which control the admission of steam through the pipes K and K' respectively to act as a gaseous piston in 10 each of the traps G or G', to raise and discharge the liquid contents thereof into the top of the keir, and which after the performance of this function, again shut off the access of steam to such trap, are preferably 15 constructed as puppet-valves so arranged as to be normally aided to keep their seats by the steam-pressure exerted upon them.

The valve-operating mechanism shown in Fig. 2 and Fig. 3 consists mainly of an electric motor R or some other suitable generator of power adapted to rotate at a uniform speed a driving shaft S which through a train of reducing gears comprising the worm s and spur-wheel t upon the shaft u, the 25 worm v and spur-wheel w upon the shaft x, revolves two separate disks y and y' affixed to the shaft x. Each of these disks carries upon its face a series of tappet-pins z or z' which are located both radially and angularly 30 equidistant from the axis of revolution, and which as the disk revolves engage successively with the upper surface of an adjustable cam-piece T or T' mounted upon a vertically sliding plate U or U' and interposed in their path. This cam-carrying plate is fixed to the upper end of the spindle, 35 of the valve L or L' and as it is depressed it gradually opens such valve against the pressure of the steam, and when it is permitted 40 to rise it allows the valve to close again. As an aid to the closure of this valve it is provided with a spiral spring V, which is located beneath it in the valve-box and which tends constantly to urge it upward toward 45 its seat.

By these means the steam valve L or L' is periodically caused to be opened and closed at regular and uniform intervals of time.

Moreover, this valve-operating mechanism 50 is so timed in its action that neither of the two steam-valves thus controlled by it shall begin to open before the other steam-valve has become closed, and that as brief an interval of time as is practicable shall elapse 55 between the closing of one valve and the opening of the other. But as the rate at which the bleaching liquor drains away from the grating of the keir and flows into the trap which is ready to receive it, differs 60 quantitatively according to the relative density of the mass of textile materials through which such bleaching liquor has had to percolate, the liquid contents of each trap accumulated during a single fixed period of 65 flow of the drainage liquor into it will like-

wise vary in amount from one bleaching batch to another and will consequently require a correspondingly different time for its return into the keir again. Hence, the period allowed to each of the steam-valves L and 70 L' for its operations from the beginning of its opening to the end of its closing should be sufficient to accommodate the maxima of such fluctuations in the liquid contents of the traps; and this allowance necessarily interferes to some degree with the attainment of entire continuity in the return of the drained bleaching liquor into the top of the keir under all conditions; but nevertheless by careful and intelligent construction and pre-adjustment of the mechanism for operating the steam-valves as hereinabove described the circulation of the bleaching liquor may be maintained at a quantitative rate approximately commensurate with and for all 75 practical purposes equal to the rate of its drainage from the mass of textile materials to be bleached in the keir.

It is obvious that the present invention is not dependent upon the specific construction of the steam-valves which control the pumping functions of the traps nor upon the specific construction of the mechanism by which those valves are automatically operated; provided, that such operating mechanism is efficiently capable of opening and closing such valves alternately and with periodic regularity, and that the valves themselves are suitably adapted to let on and to shut off steam under pressure. 90

Furthermore, it is likewise evident that the bottom of the keir might communicate with more than two traps such as those already hereinbefore described through an equal number of ducts each furnished with its own check-valve. In that case the mechanism for operating the corresponding series of steam-valves would have to provide for opening and closing them successively in a regular periodic cycle; so that only one trap 100 at a time would be closed for performing its pumping function while all the remaining traps would be open to receive the free flow of the drained liquor gravitating into them. This plurality of traps and of their ap- 105 purtenances might enable the slight interruptions in the continuity of the circulation of the bleaching liquor when using an apparatus with only two traps, to be still further diminished; but it would hardly be attended with practical advantages compensating for the structural additions. 110

In constructing the circulating apparatus herein described it is important that the traps be located with their bottoms on the 115 same level and far enough below the level of the drainage grating in the keir to accommodate the flow of the bleaching liquor into each trap without rising to a height which would flood such grating; and that 120 125 130

each duct leading from the bottom of the keir be made to enter its trap as near as practicable to the bottom of the latter in order that at the close of each pumping action performed by either trap the level of the drained liquor may stand above the check-valve of the duct leading to such trap so as to prevent any vacuum arising therein by the condensation of steam, from being 10 communicated directly to the space below the drainage grating.

The circulating apparatus thus constituted, by means of which the bleaching liquor as it drains away from the mass of 15 textile materials in the keir is caused to gravitate of itself, except as its flow may be influenced by steam-pressure within the keir, into separate receptacles wherein consecutive portions of it are respectively segregated 20 and temporarily confined and are thence conveyed and delivered in practically continuous succession into the upper part of the keir, in such manner as to insure a circulation of the bleaching liquor at a quantitative rate approximately equal to that of its 25 drainage and consequently to maintain substantially constant the quantity of bleaching liquor in contact with and percolating through the mass of textile materials to be 30 bleached within the keir, effects an economy in the operation of keir-bleaching which has never before been attained. Indeed in 35 comparison with other keir-bleaching apparatus of the best construction and efficiency hitherto employed the apparatus herein described as embodying my present invention is able to accomplish equally good results in a notably much shorter time.

I claim:

40 1. In the process of keir-bleaching the method of maintaining substantially constant the quantity of bleaching liquor in contact with and percolating through the mass of textile materials to be bleached within the 45 keir, which consists in causing the bleaching liquor as it drains away from such mass of textile materials, to flow of itself by virtue of its own gravitation into separate receptacles wherein consecutive portions of it are 50 respectively segregated and temporarily confined, and then in conveying and delivering the several different portions thus segregated and confined in practically continuous succession one after another, into the upper part 55 of the keir, in such manner as to insure a circulation of the bleaching liquor at a quantitative rate approximately commensurate with that of its drainage.

2. In the process of keir-bleaching the 60 method of maintaining substantially constant the quantity of bleaching liquor in contact with and percolating through the mass of textile materials to be bleached within the keir, which consists in causing the bleaching liquor as it drains away from such mass of

textile materials to flow of itself by virtue of its own gravitation into either of two separate liquid-holding receptacles of which one or the other is always open to receive such flow, and then in raising and discharging the 70 liquid contents of these receptacles alternately and successively into the top of the keir in such manner as to insure practical continuity in the circulation of the bleaching liquor at a quantitative rate approximately 75 equal to that of its drainage.

3. In combination with a bleaching keir, an apparatus for circulating the bleaching liquor, comprising two separate ducts leading from the bottom of the keir below the 80 draining grating, each provided with a check-valve opening outward and terminating in a trap which constitutes a liquid-holding receptacle entirely closed except in so far as concerns the tubular connections herein 85 specified; a return pipe having its lower end open and located near the bottom of each trap and its upper end communicating directly with the interior of the top of the keir; a steam-pipe extending from the top of each trap to a source of steam-supply and having a valve therein to control the admission and exclusion of steam; and means whereby the valves in the two steam-pipes are alternately opened and closed during 90 predetermined and consecutive periods of time such that steam-pressure will be exerted upon the liquid contents of one trap to discharge the same into the top of the keir, while the drained bleaching liquor is free to 100 flow into the other trap, and that after the valve in the steam-pipe of the first mentioned trap has been closed, the valve in the steam-pipe of the other trap will immediately be opened to effect an exchange of functions in the cycle of operations.

4. In combination with a bleaching keir an apparatus for circulating the bleaching liquor comprising two separate traps each constituting a liquid-holding receptacle entirely closed except in so far as concerns the tubular connections therewith herein specified and each standing where its liquid contents will normally be below the level of the drainage grating of the keir; both traps having their bottoms upon the same level one with the other; two separate ducts leading from the bottom of the keir below the drainage grating into the two traps respectively and entering these as nearly as practicable to 110 their bottoms; each duct being provided with a check-valve opening toward the trap; a return pipe having its lower end open and located near the bottom of each trap and its upper end communicating directly with the 115 interior of the top of the keir; a steam pipe extending from the top of each trap to a source of steam-supply and having a valve therein to control the admission and exclusion of steam; and means whereby the valves 120

in the two steam-pipes are alternately opened and closed during predetermined and consecutive periods of time such that steam pressure will be exerted upon the liquid contents of one trap to discharge the same into the top of the keir, while the drained bleaching liquor is free to flow into the other trap;

and that after the valve in the steam-pipe of the first mentioned trap has been closed the valve in the steam-pipe of the other trap will 10 immediately be opened to effect an exchange of functions in the cycle of operations.

GEORGE BURNSIDE FLOOD.
